CLAIM

The ornamental design for a bit for a powered surgical instrument, as shown and described.

DESCRIPTION

FIG. 1 is a top, right and rear perspective view of a bit for a powered surgical instrument showing our new design, the top, left and rear perspective view being a mirror image thereof.

FIG. 2 is a top plan view thereof, the bottom plan view being a mirror image thereof.

FIG. 3 is a right side elevational view thereof, the left side elevational view being a mirror image thereof.

FIG. 4 is a rear elevational view thereof.

FIG. 5 is a front elevational view thereof.

FIG. 6 is a sectional view along lines 6—6 shown on FIG. 3 thereof.

FIG. 7 is a top, right and rear perspective view of a second embodiment of a bit for a powered surgical instrument, the top, left and rear perspective view being a mirror image thereof.

FIG. 8 is a top plan view thereof, the bottom plan view being a mirror image thereof.

FIG. 9 is a right side elevational view thereof, the left side elevational view being a mirror image thereof.

FIG. 10 is a rear elevational view thereof.

FIG. 11 is a front elevational view thereof; and,

FIG. 12 is a sectional view taken along lines 12—12 shown on FIG. 9 thereof.

The broken or dashed lines shown in the drawings are for illustrative purposes only and form no part of the claimed design.
